UNITED STATES PATENT OFFICE.

JONATHAN W. SMITH, OF SHREVE, OHIO, ASSIGNOR OF ONE-HALF TO NOAH A. WALKER, OF FORT WAYNE, INDIANA.

WATER-HEATER.

SPECIFICATION forming part of Letters Patent No. 650,801, dated May 29, 1900.

Application filed August 9, 1899. Serial No. 726,629. (No model.)

To all whom it may concern:

Be it known that I, JONATHAN W. SMITH, a citizen of the United States, residing at Shreve, in the county of Wayne and State of Ohio, have invented certain new and useful Improvements in Water-Heaters; and I do hereby declare that the following is a full, clear, and exact description of the same, reference being had to the annexed drawings, making a part of this specification, and to the figures of reference marked thereon, in which—

Figure 1 is a perspective view showing parts broken away. Fig. 2 is a transverse section 15 through line xx , Fig. 3. Fig. 3 is a longitudinal section.

The present invention has relation to water-heaters; and it consists in the different parts and combination of parts hereinafter described, and particularly pointed out in the 20 claim.

Similar numerals have reference to corresponding parts in all the figures of the drawings.

25 In the accompanying drawings, 1 represents the outer shell or jacket, which is substantially of the form shown in the drawings; but it is not absolutely necessary to provide the exact form shown, inasmuch as the objects 30 and purposes hereinafter described can be carried out without any particular reference to the exact shape and size.

Within the jacket 1 is located the inner shell or wall 2, said inner wall 2 and jacket 35 1 being spaced one from the other, as illustrated in Fig. 2, and are so spaced for the purpose of producing a water-chamber located upon the sides and top of the heater or boiler proper.

40 It will be understood that in the construction of the heater proper tie-bolts should be provided, so as to hold the jacket 1 and the inner wall 2 in proper relative positions. At the ends of the inner wall 2 are located the 45 end plates 3 and 4, and to which end plates are attached in the usual manner the water-tubes 5, said water-tubes being so connected that their front or forward ends will be higher than their rear ends, and in order to properly 50 connect the water-tubes 5 the end plates 3 and 4 are inclined, as illustrated in Figs. 1

and 2, and the positions of said ends being utilized for the purpose hereinafter described. At the ends of the plates 3 and 4 and the ends of the water-tubes 5 are located the water-chambers 6 and 7, the water-chamber 6 being extended downward at a point below the lower tier of tubes 5 and the said chamber being tapered toward its top or upper end. The water-chamber 7 is located substantially 55 as shown in Figs. 1 and 3, and, as shown, said water-chamber is tapered toward its bottom or lower end, or, in other words, the water-chambers 6 and 7 are tapered in opposite directions, by which arrangement a better circulation of water is produced.

For the purpose of preventing the heat from going directly upward between the water-tubes the deflecting-plate is provided, which deflecting-plate is 60 formed of a width to correspond substantially with the width of the space between the inner sides of the inner wall and extended to within a short distance of the rear end of the 65 boiler proper.

70 It will be understood that a sufficient space, such as 9, should be provided for the purpose of producing a proper draft.

The water is fed to the heater by means of a feed-pipe 10, said feed-pipe being connected 75 to a supply-pipe and the pipe 11 extended and connected at the bottom or lower end of the water-chamber 6, and when water is turned on it will find its way through the tubes 5 and into the chamber 7 and also into 80 the water-chamber located between the inner and outer jackets or walls. From the top or upper end of the chamber 7 is extended the pipe 12, which pipe leads to proper 85 heaters, and it will be understood that when 90 more than one heater or radiator is used branches should be connected to the pipe 12 and lead to the heaters or radiators. When the water becomes heated in the heater proper, the heated water will ascend and the cold water 95 descend, by which arrangement a circulation of water is brought about, and by locating the tubes 5 as shown and the water-chambers 6 and 7 a better circulation is produced.

If in the event it is desired to cut off the 100 water from the chamber located between the jackets, the valve 13 is produced, said valve

being located in the branch pipe 14 and said branch pipe extended downward and connected to the outer shell 1, as illustrated in the drawings.

5 Having fully described my invention, what I claim as new, and desire to secure by Letters Patent, is—

The combination of the jackets 1 and 2 spaced one from the other, the parallel inclined plates 3 and 4, water-chambers 6 and 7 tapered in opposite directions inclined pipes connected to the parallel plates a supply 11 leading to the lower end or portion of cham-

ber 6, the pipe 14 leading to the space between the jackets and provided with a valve, 15 and the pipe leading from the upper end or portion of the chamber 7, substantially as and for the purpose set forth.

In testimony that I claim the above I have hereunto subscribed my name in the presence 20 of two witnesses.

JONATHAN W. SMITH.
